UNITED STATES PATENT OFFICE.

JOHN MADDEN AND EDWIN J. CANFIELD, OF DETROIT, MICHIGAN.

SPRING-MANIPULATING TOOL.

1,386,721.

Specification of Letters Patent. Patented Aug. 9, 1921.

Application filed September 10, 1919. Serial No. 322,363.

To all whom it may concern:

Be it known that we, JOHN MADDEN and EDWIN J. CANFIELD, citizens of the United States of America, residing at Detroit, in 5 the county of Wayne and State of Michigan, have invented certain new and useful Improvements in Spring-Manipulating Tools, of which the following is a specification, reference being had therein to the 10 accompanying drawings.

The primary object of our invention is to provide a spring manipulating tool, somewhat in the form of tongs that may be easily and safely used for retracting or distending 15 a spring, particularly a spring associated with a valve to maintain the valve normally seated. Such valves may be found in connection with various types of internal combustion engines, wherein the valves control 20 the intake and exhaust of fuel and gases to and from the cylinders of the engine, and sometimes a valve seat must be cleaned, ground or renewed to insure a positive seating of the valve. To do this it is necessary 25 to either remove the valve or temporarily release the same so that the valve may be freely moved relative to the valve seat. As the valves are constantly under the influence 30 of springs whose expansive force maintains the valves normally seated, it is necessary 35 to retract or place under additional tension a spring so as to release the valve associated therewith. Some tools have been designed for this purpose but our invention aims to 40 improve the general class of such tools by providing a double acting tool that may be used without any danger of the tool slipping during its use.

A further object of our invention is to 45 provide a spring manipulating tool having novel spring engaging jaws and a novel locking member, said member being designed to lock the handles of the tool and in one instance serve as a wedge member for 50 forcing the handles apart. As with all tools of this nature the same must be constructed to withstand rough usage and at the same time embody a construction which permits of manufacture at comparatively small cost. 55 Our invention will be hereinafter more fully described and then claimed, and reference will now be had to the drawing, wherein—

Figure 1 is a side elevation of the tool 55 in position relative to a valve, for retracting a spring associated therewith;

Fig. 2 is a similar view showing the valve spring retracted and the handles of the tool locked together;

Fig. 3 is an enlarged side elevation of 60 the tool as shown in Figs. 1 and 2;

Fig. 4 is a cross sectional view of one 65 of the jaws of the tool, taken on the line 4—4 of Fig. 3;

Fig. 5 is an enlarged cross sectional view 70 of the handles of the tool, showing a locking member holding the handles against separation;

Fig. 6 is a similar view showing the locking member interposed between the handles 75 of the tool;

Fig. 7 is a perspective view of the locking member, and

Fig. 8 is a side elevation of the tool on the same scale as shown in Figs. 1 and 2, showing another manner of using the tool.

Our tool comprises a comparatively straight handle bar 1 and an angular handle bar 2, said angular handle bar having its outer angular portion 3 pivotally connected 80 to the handle bar 1 by a pin 4 or other pivotal means, so that the inner ends of the handle bars 1 and 2 may be in proximity to each other.

The outer ends of the handle bars 1 and 85 2 are forked or bifurcated to provide comparatively flat jaws 5 and 6, respectively, and these jaws are slightly concaved or curved, as best shown in Fig. 3, so as to provide a seat for the end convolutions 7 of 90 a coiled spring 8 and thus prevent the end convolutions of the spring from slipping off of the jaws of the tool, when said jaws extend between the convolutions of the spring and washers, valve heads or other 95 structures associated with a valve 9 which has its stem or rod 10 surrounded by the spring 8 and under the influence thereof.

As further increasing the gripping or seating action of the jaws, the jaws 5 of 100 the handle bar 1 have the inner edges thereof beveled or inclined, as at 11, to provide faces on which the convolutions of a spring may easily seat and thus permit of the jaws conforming to the angular disposal of the 105 convolution of the spring. This will be again referred to when considering the use of the tool.

Slidable on the inner end of the angular handle bar 2 is a locking member, comprising 110 a sleeve 12, and an arm 13 having a recess 14 and a hook 15, said recess being in the end of

the arm 13, and the hook 15 offset at one side of said arm. The sleeve 12 is loose on the outer end of the handle bar 2 and may be turned thereon or moved longitudinally of 5 said bar, the longitudinal outward movement of said locking member being limited by a head or upset portion 16 at the inner end of the bar.

Considering the use of the tool, the shape 10 of the handle bars 1 and 2 permits of the tool being conveniently used at the side of an internal combustion engine, it being a well known fact that the valve springs are often housed in the cylinder block or in- 15 closed by a cylinder head on the cylinder block rendering it extremely difficult to reach the springs by a straight pair of tongs. So, by having the handle bar 2 angular it is possible to maintain the jaws 5 and 6 in a 20 horizontal plane while the handle bars extend at an angle to such plane.

As shown in Fig. 1, the jaws 5 have been interposed between the upper convolution 7 of the spring 8 and the wall of an engine 25 body or valve head, while the jaws 6 have been interposed between the lower convolution 7 of the spring 8 and pin 17, washer or other device carried by the valve rod or stem 10. By shifting the inner ends of the han- 30 dle bars 1 and 2 toward each other, the spring 8 may be compressed or retracted, as shown in Fig. 2, and by placing the hook 15 of the locking member in engagement with the handle bar 1, the tool may retain 35 the spring in a retracted position, thereby liberating the valve rod or stem 10 so that the valve 9 may be freely raised, rotated or removed. In so using the tool, the jaws 5 and 6 are moved toward each other to com- 40 press the spring 8, but in some instances it is necessary to move the jaws 5 and 6 away from each other to compress the spring, as

shown in Fig. 8. In this instance, one set of jaws is placed between the adjacent end convolutions of the spring and the other set of 45 jaws between a valve head or engine body. The locking member is then positioned be- 50 tween the handle bars 1 and 2 so that the handle bar 1 will engage in the recess 14 of the locking member, as shown in Fig. 6. By pushing inwardly on the locking member it has a wedging action between the handle bars 1 and 2 to separate said handle bars and thereby separate the sets of jaws 5 and 6, so that while one set of jaws is held the 55 other set of jaws will compress or retract the spring and release the valve rod or stem.

We attach considerable importance to the locking member as it prevents the handle bars from injuring the hands manipulating 60 said bars by said handle bars slipping during the operation of compressing, retracting or distending a spring.

One embodiment of our invention has been illustrated, but it is to be understood that the 65 structural elements are susceptible to such variations and modifications as fall within the scope of the appended claim.

What we claim is:—

The combination of tongs having pivot- 70 ally connected handles with one of said han- dles provided with a head, a sleeve loose on the handle to slide between the head and the pivot of the handle, and an arm carried by said sleeve and having a recess to receive the 75 other handle and prevent a closing move- ment of said handles.

In testimony whereof we affix our signatures in presence of two witnesses.

JOHN MADDEN.
EDWIN J. CANFIELD.
